CLOTHESLINE COVER

Helen D. Berezka, R.R. 2, Wausauke, Wis.
Filed June 9, 1961, Ser. No. 116,199
3 Claims. (Cl. 211—180)

This invention relates to a cover or shielding means and, more specifically, the instant invention pertains to a clothesline cover specifically designed to protect garments, bedding, and other objects normally suspended from a clothesline from rain, sleet, snow, dirt, dust and soot, while the suspended articles are drying. Thus, one of the primary objects of this invention is to provide a clothesline cover to protect garments and other articles suspended therefrom, during the drying or airing thereof, from inclement weather conditions, dust, dirt, soot, and other debris, the cover being formed of a lightweight waterproof material.

Another object of this invention is to provide a device of the type described which is held out of contact with the articles suspended from a clothesline.

A further object of this invention is to provide a device of the type described supra, which may be easily converted into a tent or other shelter.

Still another object of this invention is to provide a clothesline cover formed of a plastic or waterproof fabric material and which may be readily folded into a compact unit occupying a relatively small space.

This invention contemplates, as a still further object thereof, the provision of a clothesline cover which is non-complex in construction and assembly, inexpensive to manufacture, and which is durable in use.

Other and further objects and advantages of the instant invention will become more evident from a consideration of the following specification when read in conjunction with the annexed drawings, in which:

FIGURE 1 is a perspective view of a clothesline cover constructed in accordance with the instant invention;

FIGURE 2 is an enlarged detail cross-sectional view of the cover shown in FIGURE 1, FIGURE 2 being taken substantially on the vertical plane of line 2—2, looking in the direction of the arrows;

FIGURE 3 is an enlarged detail fragmentary cross-sectional view, FIGURE 3 being taken substantially on the vertical plane of line 3—3 of FIGURE 2, looking in the direction of the arrows;

FIGURE 4 is an enlarged detail fragmentary cross-sectional view, FIGURE 4 being taken substantially on the vertical plane of line 4—4 of FIGURE 3, looking in the direction of the arrows;

FIGURE 5 is an enlarged detail cross-sectional view illustrating a clothespin operatively engaging and holding an article on a clothesline;

FIGURE 6 illustrates, in perspective, the use of the clothesline cover as a tent or other analogous type of shelter;

FIGURE 7 is a fragmentary perspective view of the underside of the clothesline cover;

FIGURE 8 is a fragmentary exploded perspective view of the clothesline cover; and

FIGURE 9 is a fragmentary top plan view illustrating the pattern from which this clothesline cover is constructed.

Referring now more specifically to the drawings, reference numeral 10 designates, in general, a clothesline cover constructed in accordance with the teachings of this invention. The cover 10 is designed to be extended over a plurality of horizontally-extending clotheslines assigned reference numeral 12. In a preferred embodiment, the cover 10 is formed of a plurality of elongated, substantially rectangular panels 14, 16, 18, 20, 22, and 24. The

2

number of panels will vary, of course, in accordance with the number of lines 12.

To precisely spell out the construction of this cover, reference will be made specifically to the panels 20, 22, and FIGURES 1, 4, 5, 7 and 8. In these figures, it is seen that the opposed ends of each panel are reverted, as at 26, 28, and 30, 32, and are secured as by stitching. At each end of each pair of adjacent panels 20, 22, for example, the marginal edges thereof, are folded to form the abutting elements 34, 36 which are secured together by stitching, or other desirable means. Interposed between the elements 34, 36 and again at each end of each pair of adjacent panels is a pocket 38 having a convoluted form.

15 Each pocket 38 includes a pair of oppositely-disposed outer side walls 40, 42 and a pair of inner side walls 44, 46, the latter being joined at their upper ends by a bight 48. The outer side wall 40 connects with its adjacent inner side wall via a bight portion 50, and in a similar manner, the outer side wall 42 connects with its adjacent inner side wall 46 through the bight 52. The pockets 38 are preferably sewn at their open ends, as is indicated at 54, to effect a closure thereof. The upper edges of each of the outer side walls are reverted, as at 56, 58, and are stitched at 60, 62 between the elements 34, 36.

Intermediate the pockets 38 at each end of each adjacent pair of panels is an elongated housing, generally designated by the reference numeral 64 (see FIGURES 5, 7 and 8). The housing 64 comprises an insert which includes an elongated inverted, substantially U-shaped plastic member which, in its operative position, is substantially upright, as is seen in FIGURES 5, 7 and 8. As such, the housing or insert 64 comprises a pair of oppositely-disposed side walls 66, 68 connected at their respective upper ends by a bight portion 70. The lower ends of each of the side walls 66, 68 are folded to form outwardly-diverging flaps 72, 74 which are connected by a line of stitching 76 to the elements 34, 36. The side walls 66, 68 are collapsible toward each other to an inoperative position wherein the same may be folded against an adjacent panel in the manner shown in FIGURE 6, and as is represented by reference numeral 64'. To maintain this position, the side walls 68 and the panel adjacent thereto are furnished with the conventional snap fasteners 78, 80.

Loops or rings 82 are secured to the centermost one of the housings 64 to serve a purpose to be described.

Each of the panels 14 and 24 has secured thereto a bias tape 84 on their remotely-disposed longitudinally-extending marginal edges, and the panels and tapes have a plurality of longitudinally-extending spaced grommets 84' extending transversely therethrough which also serve a function to be described.

To prevent the side walls 14, 24 from flaring outwardly under wind pressures, or other adverse weather, their respective adjacent lower ends are connected together by tie cords 86 connected to the lower ends thereof.

FIGURE 9 illustrates the simplicity of the construction of the cover 10. As shown herein there is the depending panel 24 which is provided with hems or reverted marginal edge portions shown in broken lines, and designated by the reference numerals 30, 88. To the base or lower edge of the panel 24 is secured the bias tape 84 referred to above. Interposed between the panel 24 and the panel 22 are the pockets 38 and the housing 64, each of which is shown as being formed of rectangular strips of material 90, 92. The strips 90 are folded on lines 94, 96 to provide the reverted portions 56, 58 of the pockets 38, and are again folded at 98, 100, 102 to form the bights 50, 52 and 48, respectively.

Each of the housings or inserts 64 is formed from the strip of material 92 and is folded on lines 104, 106 to

provide the flaps 72, 74, and is again folded at 103 to form the bight portion 70.

The clothesline cover 10 is adapted to be extended over the clotheslines 12 in such a manner that the side walls 44, 46 of the pockets 38 straddle the lines 12 and with each of the housings 64 opening downwardly on one of the lines, as is shown in FIGURE 5. The cover 10, reference being made to FIGURE 4, after once being placed in position on the lines 12 is detachably connected thereto by means of clothespins 110 which are inserted in the pockets 38 and extend over the bights 48 with the legs 112, 114 disposed intermediate the pairs of outer and inner side walls 40, 44 and 42, 46, respectively. The individual housings 64 are unsnapped and raised to their elevated positions, as needed, the housings 64 being designed to accommodate the upper ends of other clothespins 110' (see FIGURE 5), the legs 112', 114' which are superimposed over a garment or other article 116 being draped over one of the lines 12.

The cover 10 has many practical uses aside and apart from a clothesline cover. For example, the same may be used as a play tent 118 supported on lines 12' and guyed to the ground by lines 120 and anchoring pins 122' (see FIGURE 6). One of the respective ends of the lines 120 extend through selected ones of the grommets 84'.

Additionally, the cover 10, if draped over a single line 12, will provide privacy in small yards in crowded areas, and several of the covers 10, taken together, and colored, will serve as a suitable background for any occasion.

The rings or loops 82 provide means for connecting the cover 10 to a curtain rod for a shower curtain and also provide means for hanging the same for storage purposes.

Having described and illustrated two embodiments of this invention, it will be understood that the same are offered merely by way of example, and that this invention is to be limited only by the scope of the appended claims.

What is claimed is:

1. A clothesline cover for extension over a plurality of laterally-spaced substantially parallel clotheslines comprising an elongated substantially rectangular sheet of water-impervious flexible material, said sheet including a plurality of elongated laterally-spaced housings disposed over and opening downwardly toward said clotheslines, means releasably securing said sheet on said clothes lines, and said sheet having a width sufficient to overlie the remotely-disposed pair of clotheslines and to depend therefrom to form a pair of protective side panels.

2. A clothesline cover for a plurality of elongated laterally-spaced and substantially parallel clotheslines comprising a plurality of elongated substantially rectangular panels formed of water-impervious flexible material, said panels being disposed in side-by-side relation, means connecting each adjacent pair of panels, a housing interposed between each adjacent pair of panels and connected thereto, each of said housings extending upwardly over one of said clothes lines, and means releasably connecting said panels at each end thereof with said clotheslines.

3. A clothesline cover as defined in claim 2, wherein said last-named means comprises a normally upright pocket having a pair of adjacent confronting inner walls and a pair of remotely-disposed outer walls, bight means connecting the upper ends of said inner walls, and bight means connecting the lower ends of each adjacent pair of inner and outer walls.
